DANIEL G. SAUNDERS, JR., OF KANSAS CITY, MISSOURI.

EXTENSION-TELEPHONE.

1,189,001.

Specification of Letters Patent. Patented June 27, 1916.

Application filed October 3, 1914. Serial No. 864,905.

To all whom it may concern:

Be it known that I, DANIEL G. SAUNDERS, Jr., a citizen of the United States, residing at Kansas City, in the county of Jackson 5 and State of Missouri, have invented certain new and useful Improvements in Extension-Telephones; and I do declare the following to be a full, clear, and exact description of the invention, such as will 10 enable others skilled in the art to which it appertains to make and use the same, reference being had to the accompanying drawings, and to the letters and figures of reference marked thereon, which form a 15 part of this specification.

My invention relates to extension telephones, and has for its principal object to provide a device of this character whereby telephone service may be had from different 20 parts of a building otherwise than by the use of a plurality of instruments. In accomplishing this object I provide a plurality of base circuit members, all of which lead to a common line circuit, together with 25 a portable extension set comprising the instrument and a wall box which is adapted for co-operation with any one of the circuit base members and which may be carried from room to room, or to various parts of a 30 building, to provide the several extension services without the necessity for a separate wall box for each individual extension.

In the drawing, wherein the preferred form of my invention is illustrated, Figure 35 I is a perspective view of an extension outfit comprising a base circuit member, which I will hereinafter term a wall board, a wall box and instrument. Fig. II is a rear perspective view of the portable wall box. Fig. 40 III is a front perspective view of a wall board. Fig. IV is a vertical section of the wall board and box showing the support of the box and the contacts between the wall board and box. Fig. V is a detail section 45 showing the insulated mounting of the binding posts in the wall board. Fig. VI is a similar view of the box parts.

Referring more in detail to the parts:— 1 designates the wall board, which may be 50 mounted in any suitable manner, preferably vertically, on the wall of a room or building, and is provided with spaced binding posts 2, having connection with telephone line wires 3, and having contact heads or points 4; 55 the connection of the line wires being made

at the back of the board and the contact points being exposed at the front thereof to conceal the wire and expose the contact points. The board 1 is provided above the contact points with apertures or sockets 5 60 for receiving the supporting lugs of a wall box 6, which latter may be of any ordinary construction, and contains the ordinary ringing coils 7 and condenser 8. At the back of the box 6 is a pocket 10, and extending 65 through the pocket are binding posts 11, which are connected by wires 12 with proper terminals in the instrument, and fixed to the box, within the pocket 10, are contact lips 14 which are spaced from each other and 70 from the base of the pocket, and are insulated from the latter by a fiber, or like, mat 15. The lips 14 are preferably of spring material and have loose free ends bowed outwardly from the base of the pocket to contact with the heads or contact points 4 of the binding posts 2 on the wall board 1, when the parts are assembled. On the back of the wall box 6 are outstruck lugs 17 which are adapted for projection into the apertures or sockets 5 in the top of the wall board to support the box; the arrangement of the lugs and contact lips 14 being such that when the box is supported on the wall board the contact lips will touch the contact heads of the binding post 2 to complete a circuit through the contained parts of the wall box. It is apparent that with this construction the box will have a limited pivotal mounting on the wall board and that the 90 contact of the box lips and board points will be insured by the pivotal action of the wall box toward the board.

The wall box comprises the ordinary bells 19 and a suitable transmitter and receiver, 95 which may consist of a desk set instrument or which may be mounted directly on the box itself.

In order to adapt my improvements to boxes of any ordinary construction, and preferably those which have gone into use prior to their equipment with the improvements, I prefer to form the pocket 10 and lugs 17 in a separate plate 22, which may be attached to the box 1 by bolts 23, or the 105 like, whereby the box is ordinarily permanently attached to the wall board.

While I have described my improvements as comprising members wherein the wall board carries the sockets 5 and posts 2, it is 110

readily apparent that the sockets and posts may be on the box and the lugs and spring contacts on the wall without in any way departing from the spirit of my invention.

- 5 In using the device, presuming the parts to be constructed as described, and the boards 1 mounted at various portions of a building, such as within the various rooms of a residence, the box may be projected 70
10 on one of the wall boards with the points in contact, so that the circuit is closed through the instrument to enable the latter to be used in the ordinary manner. Should it be desired to use the telephone in a different room, or portion of a building, the box 75
15 may be removed from the wall board; preferably by means of a handle 20, and the box and instrument carried to the point where the use is desired and mounted on 20
20 the wall board at that location, by dropping the box lugs into the board apertures, so that the box is supported, and its lower portion will swing back to secure contact of the boss lips with the board points. When in 25
25 the latter position, the contacts are made and the instrument may be used.

It is apparent that as many boards may be provided as may be necessary or desirable, and that but one wall box and instrument are required, thereby eliminating the greatest expense incident to the use of a plurality of telephones, and insuring clear service because of the relatively short extension circuit between the wall box and instrument. 35

Having thus described my invention, what I claim as new therein, and desire to secure by Letters-Patent, is:—

1. The combination with a wall board 40 having contact points, of a portable instrument box having swinging support on the wall board and having contact points urged to engagement with the points on the wall board by weight of the box on its swinging 45 support.

2. The combination with a wall board, of contact points at the lower portion of the board, a portable instrument box having swinging support from the upper portion 50 of the wall board, and contact members at the lower portion of the box urged to engagement with the board contacts by weight of the box.

3. The combination with a wall board 55 and portable instrument box, one having supporting lugs and the other having sockets for receiving the lugs, to support the box, and contact members on the board and box, with one set of contact members projected from its carrying part to engage the other set.

4. The combination with a wall board 60 and portable instrument box, one having supporting lugs and the other having sockets for receiving the lugs, to support

the box, and contact members on the board and box, with one set of contact members projected from its carrying part to engage the other set; the projected contacts being flexible, for the purpose set forth. 70

5. The combination with a wall board having a supporting portion and contact points, of a portable instrument box, a back plate inclosing the back of the box, and having a supporting portion adapted for co-operation with the relative portion on the wall board to support the box therefrom, and contact points on the back plate spaced from the supporting portion and engaging the board contacts when the box is supported on the board. 75

6. The combination with a wall board having apertures therein and having contact points spaced from the apertures, of a portable instrument box, a back plate inclosing 80 the box at the rear and having downwardly and rearwardly struck lugs adapted for projection into the wall board apertures to support the box, and contact points on the rear of the back plate adapted for engaging 85 the wall board contacts when the box is supported from the wall board.

7. The combination with a wall board having a supporting portion and contact points, of a portable instrument box having 90 a supporting portion whereby the box is hung from the supporting portion of the wall board, and having a socket, contact members anchored in the socket and having free ends projecting from the socket and 95 engaging the wall board contacts when the box is supported upon the board. 100

8. The combination of a portable telephone box and a wall board, means for supporting the box upon the board, said means 105 comprising lugs on one member and co-operating receiving sockets on the other member; said lugs or sockets being tapered to guide the co-operating supporting members into accurate position when the box 110 is supported upon the board.

9. In a portable telephone box, a wall board, electric contacts on the box and co-operating contacts on the board, means for supporting the box upon the board, said means comprising lugs on one member and co-operating receiving sockets on the other member, said lugs or sockets, or both, being tapered to guide the co-operating parts into accurate position when the box is supported 115 upon the board. 120

10. The combination with a wall board having its front face spaced from a supporting wall, and having a supporting portion on its face, electric terminals on the face of the board, said terminals being connected to line wires; a portable box, telephone apparatus within the box, a supporting portion at the back of the box adapted to co-operate with the supporting portions on the 125 130

board, and electric terminals at the back of the box connected with telephone apparatus within the box and adapted to form contact with the terminals on the board when the box is supported on the board.

11. A wall board having its face spaced from a wall, supporting means on the face of the board, electric terminals on the face of the board connected to line wires and spaced from the supporting means on the board, a box adapted for support on the board, telephone apparatus within the box, electric terminals at the back of the box connected with the telephone apparatus within the box and adapted to form contact with the terminals on the board when the box is supported on the board.

12. A wall board having its face side spaced from a wall, supporting means on the face of the board, electric terminals on the face of the board passing through the board, line wires connected with the terminals at the back of the board, a portable box, telephone apparatus within the box, supporting means at the back of the box adapted to coöperate with the supporting means on the board, electric terminals on the back of the box connected with the telephone apparatus within the box and adapted to form contacts with the terminals on the board when the box is supported on the board.

13. The combination of a portable box, telephone apparatus within the box, contacts at the back of the box and connected with the apparatus within the box, a wall board pierced to permit the passage of electric contacts through the board, contacts arranged to coöperate with contacts on the box, means for connecting line wires to the contacts at the back of the wall board, and means for supporting the box on the wall board so that the contacts on the back of the box coöperate with the contacts on the board and make the proper connections between the line wires and the apparatus within the

box when the box is supported on the wall board.

14. The combination with a wall board having a supporting portion and contact points, of a box comprising an inclosing portion and an auxiliary back attached to the inclosing portion, and contact members adapted for coöperation with relative members on the wall board.

15. The combination with a wall board having a supporting portion and contact points, of a box having an auxiliary back provided with a pocket and a supporting portion, and contact members mounted in the pocket and adapted for coöperation with like members on the wall board when the supporting portion of the auxiliary back is in operative relation to a relative portion on the wall board.

16. The combination with a wall board and a box back plate, one having lug sockets and the other lugs for supporting engagement in the sockets and both having contact points arranged for coöperative engagement when the back plate is supported from the wall board, and an instrument box attached to and supported by the back plate.

17. The combination with a wall board having its front face spaced from a supporting wall, and having a supporting portion, electric terminals on the board, said terminals being connected to line wires: a portable box, telephone apparatus within the box, a supporting portion on the box adapted to coöperate with the supporting portion on the board, and electric terminals at the back of the box adapted to form contact with the terminals on the board when the box is supported on the board.

In testimony whereof I affix my signature in presence of two witnesses.
